INVENTOR

HOWARD E. COFFIN

UNITED STATES PATENT OFFICE.

HOWARD E. COFFIN, OF DETROIT, MICHIGAN, ASSIGNOR TO E. R. THOMAS
DETROIT CO., OF DETROIT, MICHIGAN, A CORPORATION OF MICHIGAN.

DESIGN FOR AN AUTOMOBILE-BODY.

No. 38,800.

Specification for Design.

Patented Sept. 10, 1907.

Application filed September 1, 1906. Serial No. 333,021. Term of patent 7 years.

To all whom it may concern:

Be it known that I, HOWARD E. COFFIN, a citizen of the United States of America, residing at Detroit, in the county of Wayne and State of Michigan, have invented a certain new, original, and ornamental Design for an Automobile-Body, reference being had to the accompanying drawings, in which—

Figure 1 is a perspective view showing the design, and Fig. 2 is a side elevation.

I claim:

The ornamental design for an automobile body, as shown.

HOWARD E. COFFIN.
